UNITED STATES PATENT OFFICE.

EVERETT C. KLINE, OF NORWOOD, OHIO, ASSIGNOR TO THE VICTOR SAFE & LOCK COMPANY, OF CINCINNATI, OHIO, A CORPORATION OF OHIO.

CLOSURE-PREVENTIVE DEVICE FOR VAULT-DOORS.

1,187,152.

Specification of Letters Patent. Patented June 13, 1916.

Application filed April 3, 1916. Serial No. 88,475.

To all whom it may concern:

Be it known that I, EVERETT C. KLINE, a citizen of the United States, residing at Norwood, in the county of Hamilton and State 5 of Ohio, have invented certain new and useful Improvements in Closure-Preventive Devices for Vault-Doors, of which the following is a specification.

My invention relates to devices whereby 10 the unauthorized closing and locking of vault doors may be prevented.

In daylight bank robberies, it is a fairly common occurrence for the burglars to lock the cashier or other official in the vault. My 15 invention is devised to furnish a simple and inexpensive means whereby the locking of the vault door by the burglar is rendered impossible, or exceedingly difficult of attainment by the burglar in the time at his disposal. Accordingly I provide a locking device operable by a key or suitable implement which is retained by the cashier, whereby a revoluble shaft or other moving part carried by the door may be locked, after the vault 20 has been opened in the morning, the result being that the door cannot be fully closed or locked. I prefer to apply my improved locking device to the pressure system, which is commonly used on vault doors, to lock one 25 of the revoluble shafts of the pressure system in such a position as to prevent the seating of the door into a position in which the bolts may be shot.

In order that a clearer understanding of 30 my invention may be had, attention is hereby directed to the accompanying drawings forming part of this application and illustrating certain embodiments of my invention.

40 In the drawings Figure 1 represents a partial front elevation of a vault door having my improved device applied to one of the pressure bars or shafts; Fig. 2 is an enlarged vertical section taken on line 2—2 of Fig. 1; Figs. 3 and 4 are sections taken on lines 3—3 and 4—4, respectively, of Fig. 2; Fig. 5 is a partial end elevation of the casting shown in Fig. 2, with the outer cap removed; Fig. 6 is a plan view of the cap, the 45 cover plate being partly broken away; and Fig. 7 is a side elevation of a key which may be used in operating the device.

Referring to the drawings, the door 1 is adapted to seat against the door frame 2, 50 having a jamb member 3. The door is rep-

resented as being carried by the usual pivoted crane 4. The door is understood to carry bolt-work, operated by handle 5 on shaft 6, and a combination lock, operated by the dial 7, as well as the pressure system, all 55 of which parts may be of usual or well-known construction. The pressure system is illustrated as comprising a hand-wheel 8 mounted on worm shaft 9, which rotates vertical shaft 10, which is geared to the horizontal pressure shafts, one of which is illustrated at 11. Shafts 10 and 11 are illustrated as connected by bevel gears 12, 12. Shaft 11 is journaled in brackets 13, 13 on the face of the door and is provided at its 60 outer end with the eccentric pin or cam 14. Pin 14 is adapted to enter the opening 15 in the lug 16 mounted on the jamb, when shaft 11 is in proper angular position to aline pin 14 with opening 15. Lug 16 is provided 65 with an undercut recess, with which the eccentric pin 14 coacts, when located therein, the rotation of hand-wheel 8 in such case serving to press the door tightly against its seat. When pin 14 is not alined with opening 15, it abuts against the outer face of lug 16, when the door is pressed toward closed 70 position, so that in this case the door cannot be closed sufficiently to enable the bolts to be shot into locked position. In the form of 75 my invention illustrated, I provide means for locking shaft 11 in the position illustrated, in which it is impossible to aline pin 14 with opening 15.

As illustrated a casting or bracket 17 is 80 bolted to the face of the door by bolts 18 extending through openings 19 in base portions 20 of the casting. Shaft 11 extends through a central cylindrical opening in casting 17, and a locking pin 21 extends into 85 the casting at right angles to shaft 11 and adjacent thereto. Shaft 11 is provided with a curved recess 22 extending across the periphery of the same within its bearing in casting 17. Locking pin 21 has a curved 90 depression 23 milled or otherwise formed longitudinally of the same, this depression being curved to the same radius as shaft 11. Pin 21 is so positioned that the solid portion of its periphery may extend through the 95 recess 22 in shaft 11, as is shown in Fig. 2, to lock shaft 11 against rotation. When, however, pin 21 is rotated through 180° the 100 curved depression 23 of pin 21 will lie in alinement with the circular wall of the open- 105 110

ing in the casting 17 through which shaft 11 extends, thus permitting the rotation of shaft 11.

Locking pin 21 is provided with an end portion 24 of reduced diameter, having a slot 25 in its end, into which a screw-driver or the like may be inserted to rotate pin 21 into its locking or unlocking position. A sleeve 26 is mounted in the outer end of the opening through which pin 21 extends, and positioned against the shoulder 27 of pin 21, to prevent removal of the latter. Sleeve 26 may effectively be mounted in position by forming the same with a screw-threaded periphery and forming the opening in which the screw is mounted with a corresponding internal screw-thread 28. One portion 29 of the sleeve is formed longer than the other portion 26' and thus forms an abutment for the small screw or pin 30 extending from the periphery of the end portion 24 of the locking pin. When screw 30 is in the position shown in Fig. 5, abutting against the lower end of the portion 29 of sleeve 26, pin 21 is in its locking position, and when pin 21 is rotated in a clockwise direction through 180° into its unlocking position, screw 30 will abut against the upper left hand end of portion 29, referring to Fig. 5. The lower portion 26' of sleeve 26 is sufficiently reduced in length to permit the movement of screw 30 past the end of the same, as is shown in Fig. 2. A slot 31 may be cut in the end of the sleeve, between the portions 26' and 29 thereof, to form a seat for a screw-driver, to permit the sleeve being screwed into position.

A cap member 32, preferably cylindrical in form, is adapted to fit closely within a suitable recess in the end of casting 17, in line with locking pin 21, to prevent access to the latter when the cap is in position. This cap member is adapted to be removed by a key, such as is shown at 33 in Fig. 7, and comprises a bearing portion 34 and a cover plate 35 secured thereto by screws 36. A pin 37 having a block 38 formed integral therewith is slidably mounted in a rectangular recess 39 on the inner face of member 34 of the cap. A spiral spring 40 surrounds the pin beyond one end of the block, the spring bearing against the inner end of the block at one end and against an end of the recess at the other end. The spring thus forces the pin and block to the right, referring to Figs. 3 and 6, with the right hand end of the pin extended through an opening in the member 34. When the cap is mounted in position, as is shown in Fig. 3, the end of pin 37 extends into a suitable opening in casting 17, thus locking the cap in position. The block 38 is cut away on the side thereof adjacent cover plate 35, as is shown at 41, this cut-out portion 41 being in line with 65 but somewhat longer than the key-hole 42

formed in cover plate 35. The key 33 is provided at its end with a lug 43 extending to one side, the end 44 of the key being slightly less in length than the recess 41 and slightly greater in length than the slot 42. 70 The key is flat and of a thickness less than the width of key-hole slot 42.

When it is desired to operate the device, the key is inserted through key-hole 42 at an inclination, so that the toe 43 of the key 75 abuts against the shoulder 45 of recess 41, whereupon the key may be straightened out, the engagement of the rounded heel 46 of the key with the opposite end 47 of slot 42 camming block 38 to the left, so that pin 37 80 is withdrawn from locking engagement with casting 17, against the pressure of spring 40. The cap may now be withdrawn by a direct pull on the key, whereupon the key may be released from the cap by tilting the key to 85 the left. The end 44 of the key may then be applied to the slot 25 in the end portion of the locking pin 21 and the latter rotated through half a revolution to lock or unlock shaft 11 as desired. 90

In the operation of the device, pin 21 is placed in its unlocking position, with its circular notch 23 in registration with the cylindrical opening in member 17, through which shaft 11 extends, when it is desired 95 to lock the door. Shaft 11 may then be rotated into position permitting the eccentric pin 14 of the shaft to enter opening 15 in lug 16, so that the door may be bolted, locked, and the pressure system applied for 100 the night. In the morning, after the vault has been opened, the cashier may remove cap 32 with his key, and then apply the end of the key to slot 25 to rotate pin 21 into the position shown in Fig. 2 in which the 105 pin extends through notch 22 in shaft 11, shaft 11 being first rotated into proper position to aline notch 22 with the locking pin. A screw 48 may be provided on shaft 11, to be alined with a suitable mark (not shown in the drawing) on the side of casting 17, to show when shaft 11 is in proper angular position to be locked by pin 21. The cap 32 is then replaced, shaft 11 now being in such 110 angular position as to prevent the complete closing of the door. In case of robbery, rotation of shaft 11 without the use of a key similar to key 33 will prove a matter of considerable difficulty. 115

It should be understood that my invention is not limited to the exact details of construction described, but that all fair equivalents of the same are included, and accordingly that my invention is as broad as is indicated by the accompanying claims. 120

Having now described my invention, what I claim as new therein and desire to secure by Letters Patent is as follows:—

1. In vault construction, the combination of a frame member having a door seat and 125

- a lug on the face of the jamb thereof, having an undercut recess therein, a door adapted to be closed against said seat, means for pressing the door against its seat, including
- 5 a revoluble shaft carried on the face of the door having an eccentric end portion adapted, when the door is closed, to enter said recess in one angular position of the shaft and to abut against the outer side of the
- 10 lug in another angular position of the shaft, when it is attempted to close the door, a bearing member through which said shaft extends, and means for locking said shaft in said last-named angular position, comprising
- 15 a locking pin extending into said bearing member to coact with said shaft therein, and locking means for preventing or permitting operation of said pin, substantially as set forth.
- 20 2. In vault construction, the combination of a door, a movable member carried thereby, having one position in which the door may be closed and locked and another position in which the door cannot be fully closed, said member having a notch therein, a movable locking pin adapted to extend into said notch to lock said member, said pin having a notch adapted to be alined with said member to permit movement of the latter, and key-operated cover means for preventing access to said locking pin, substantially as set forth.
- 25
- 30
3. In a vault door, the combination of a movable member having one position in which the door may be closed and locked 35 and a second position in which the door cannot be fully closed, a bearing member in which said movable member is carried, a movable locking pin mounted and entirely inclosed within said bearing member adjacent to said movable member, said pin being adapted to lock said movable member when the latter is in its second position, and locking means for preventing or permitting operation of said locking pin, substantially as set forth. 40
4. In a vault door, the combination of a revoluble shaft, having a notch therein, a bearing member through which said shaft extends, a revoluble locking pin journaled 50 within said bearing member, adapted in one position to extend through said notch and in another position to clear said shaft, said pin being entirely inclosed within said bearing member, and a key-operated closure in 55 a surface of said bearing member in line with and covering the outer end of said pin, substantially as set forth.

This specification signed and witnessed this 28th day of March, 1916.
